GEORGE HADLEY, OF BUFFALO, NEW YORK.

Letters Patent No. 65,564, dated June 11, 1867.

IMPROVEMENT IN STILLS.

The Schedule referred to in these Letters Patent and making part of the same.

TO ALL WHOM IT MAY CONCERN:

Be it known that I, GEORGE HADLEY, of Buffalo, Erie county, State of New York, have invented a new and useful Improvement in Stills; and I do hereby declare the following to be a full, clear, and exact description of the same, sufficient to enable one skilled in the art to which the invention appertains to make use of it, reference being had to the accompanying drawings, which form a part of this specification, and in which—

Figure 1 is a central longitudinal vertical section.

Figure 2 is a similar section of a modified form of the still.

The vapor from the still is conducted through a pipe which at different parts of its length is enveloped by water-jackets of gradually decreasing temperature, so as to eliminate by a regular and continuous action the particular grade of vapor for which the successive, and especially the last water-jacket, is by its temperature adapted.

In the drawings the still is marked D, the pipe *a*, the successive water-jackets C¹ C² C³ C⁴, their connecting pipes *d*. The water-supply vessel A discharges by its faucet E into the funnel F, at the head of the column of water envelopes. *d*¹ is the discharge faucet at the foot of the column. H is the pipe leading to the worm in the condenser.

The operation is as follows: Heat being applied to the still in any suitable manner, either by a steam-jacket, a coil, a furnace, or jets, the rising vapor passes into and through the pipe *a*, meeting as it proceeds with the refrigerating or condensing effect of a series of enveloping water-jackets of decreasing temperature; that is to say, the first it meets with is relatively the warmest, the contents of the jackets becoming cooler in each successive envelope as the vapor passes on its path to the condenser worm. Water of the proper temperature is admitted from the tank A to the upper jacket C⁴, fig. 1, or C⁵, fig. 2, which is thereby kept at such a temperature as to eliminate the subtle vapor which has passed with denser vapors from the still. The water passes from the highest jacket by a pipe, *d*, to the one next in a series which is at a higher temperature, from thence to the next, becoming more and more heated as it descends from point to point, and after having served its purpose in the succession of jackets, and becoming more and more heated, it is discharged at last at the foot of the column by faucet *d*¹. Any suitable number of water-jackets may be employed, and the pipe *a* may be either bent, as in fig. 1, or straight, as in fig. 2, the same feature of successive water-jackets of progressively decreasing temperature being found in each. The pipes *d* which connect the water-jackets are of such a size as not to allow a general circulation of the water to and fro between the successive jackets C C¹ C² C³ C⁴, which would tend to establish a uniformity of temperature, but merely a passage downward of the water at such a rate as will accomplish the desired purpose of giving such a gradually increasing temperature in the downward series as shall be adapted to fulfil the end in view. The degree of the increase in the temperature of the jackets is regulated by varying the supply of water, by varying the heat applied to the still, or by both. Instead of connecting the water-jackets by pipes *d*, each of the jackets may communicate with a reservoir of water maintained at the required temperature so as to make the several jackets independent. I also desire to state that I may elect to apply distinct refrigerating means to each jacket so as to render it independent of a separate reservoir, and the effect may be obtained by any circulating liquid or even mere fluid, such as a current of air properly regulated. The temperature of the water-jacket is adapted to keep back, by condensing them, all vapors which it is desired to retain in the still. The first jacket condenses a portion of the vapor, that which passes said jacket being of such levity as not to be condensable at the temperature of said jacket; the second jacket, in ascending series, being somewhat cooler, condenses a further portion, the third another portion, and so on until the last jacket is reached. The refrigerating character of this, the last condenser, is such as to allow only vapor of a given tenuity to pass to the worm, which brings it to the liquid form, after having run the gauntlet of the whole series of jackets, and having its grosser or heavier associated vapors detained on the road and returned by pipe *a* to the still.

Having described my invention, what I claim therein as new, and desire to secure by Letters Patent, is—

1. A series of jackets of graduated temperature, applied to the pipe of a still to eliminate by successive stages a fluid of given tenuity and return the heavier condensed vapors.
2. I claim a tube, *a*, leading from the still, and provided at different points in its length with a succession of condensers adapted to condense successive portions of the vapor therein.

GEORGE HADLEY.
